United States Patent Office

Des. 211,386
Patented June 11, 1968

211,386

CANDLE HOLDER OR THE LIKE

Erik H. Bertelsen, 3546 Willow St.,
Flossmoor, Ill. 60422

Filed May 31, 1967, Ser. No. 7,307

Term of patent 14 years

(Cl. D48—2)

FIG. 1 is a perspective view of a candle holder showing my new design;

FIG. 2 is a perspective view of a second embodiment of my design;

FIG. 3 is a third embodiment of my design;

FIG. 4 is a side elevational view of the candle holder of FIG. 3; and

FIG. 5 is a top plan view of the candle holder of FIG. 3.
I claim:

The ornamental design for a candle holder or the like, substantially as shown and described.
